(57) **CLAIM**

The ornamental design for a shoe sole, as shown and described.

DESCRIPTION

FIG. 1 is a bottom perspective view of a first embodiment of a shoe sole;

FIG. 2 is a left-side perspective view thereof; and,

FIG. 3 is a right-side perspective view thereof.

FIGS. 1 through 3 depict a right shoe sole, and a second embodiment is a left shoe sole, which is a mirror image of the first embodiment.

The broken lines depict environmental structure and portions of the shoe sole that form no part of the claimed design.
